UNITED STATES PATENT OFFICE.

LORETTO CORY, OF SHELBYVILLE, INDIANA.

BAT.

1,189,921.

Specification of Letters Patent.

Patented July 4, 1916.

Application filed November 24, 1914. Serial No. 873,783.

To all whom it may concern:

Be it known that I, LORETTO CORY, a citizen of the United States, residing at Shelbyville, in the county of Shelby and State of Indiana, have invented a new and useful Bat, of which the following is a specification.

This invention has reference to bats, and is designed to provide a bat with which certain ball games may be played.

In accordance with the present invention the bat is provided with a broad flat body or striking portion, from one end of which there extends a handle suitably shaped to be grasped by the hand of the user. The body portion of the bat is made longer than wide and adjacent to the handle the body of the bat is traversed by a hole or passage leading to a net forming a receptacle for a ball, and attached to the body of the bat so as to depend therefrom.

The invention will be best understood from a consideration of the following detailed description, taken in connection with the accompanying drawings forming a part of this specification, with the further understanding that while the drawings show a practical form of the invention, the latter is not confined to any strict conformity with the showing of the drawings, but may be changed and modified so long as such changes and modifications mark no material departure from the salient features of the invention.

In the drawings:—Figure 1 is a perspective view of a bat constructed in accordance with the present invention. Fig. 2 is a longitudinal central section with the handle portion shown in elevation.

In the drawings there is shown a bat comprising a body portion 1 and a handle portion 2 extending from one end of the body portion, and preferably though not necessarily in one piece therewith. The body portion 1 is made broad and flat and may be approximately twice as long as wide, although strict adherence to such particular proportions is not demanded. The handle 2 is made of convenient size and shape to be readily grasped by the hand. Adjacent to the handle 2—that is, between the center of the body portion and the handle,—the body portion is pierced by a passage 3 of a diameter to permit a ball of suitable size to freely pass therethrough. There is also provided a basket or receptacle 4 which

may be made of cotton or linen netting, and this basket is of conical form with one end closed, while the wide or mouth end of the basket is attached at its edge to the wall of the passage 3 in any suitable manner. The particular method of attaching the basket to the bat is not of importance, for any fastening device or devices or even cement may be used. Ordinarily some mechanical fastening means is employed to hold the basket firmly to the bat.

The portion of the bat on the side of the passage 3 remote from the handle 2 is quite broad and flat and is intended to support a ball during certain stages of a game for which the bat is adapted. With the ball supported upon the outer flat portion of the body of the bat an appropriate movement of the bat will cause the ball to ascend into the air, and on its fall the player endeavors to catch the ball in the flexible basket 4 by so locating the bat that the ball will drop through the passage 3 into the basket and so be retained. Should the player fail to so place the bat that it will pass into the basket, the endeavor is made to catch the ball upon the outer flat face of the bat so as to again propel the ball into the air. If the play be made by a single person the ball is driven up into the air and the endeavor is made to catch the ball in the basket, but if two or more players be engaged in the game then the ball may be propelled from player to player by striking the ball with the outer flat end of the bat, and in accordance with the manner of playing the game endeavor may be made at prearranged times to catch the ball in the basket portion of the bat, while failure to follow the prescribed plays may count as a forfeit.

With so broad a striking face as is provided by the flat longitudinally extended bat body, it is not at all difficult to strike the ball and propel it away from the bat, but it becomes considerably more difficult to so place the bat as to cause a swiftly moving ball to pass through the opening 3 and lodge in the pocket or basket 4, and this difficulty is increased by placing the basket close to the handle.

While ordinarily the bat is made of wood, and preferably, though not necessarily, of one piece of wood, other materials may be employed where found suitable for the purpose.

By making the basket of some soft mate-

rial, such as cotton or linen thread in the form of netting, the basket or pocket is readily folded into compact form and may lodge wholly within the passage 3, thus facilitating storage or transportation. The pocket, however, readily extends for the reception of the ball while the bat is being used for individual or collective play.

What is claimed is:—

- 5 10 A bat comprising a broad flat elongated body portion of greater length than breadth, with a handle projecting from one end lengthwise of the body portion, said body portion being pierced by a passage adjacent the handle end, said passage being constantly open and of a size to be readily

traversed by a ball, and a basket of soft flexible material having its mouth end attached to the body portion about the margin of the passage, that portion of the body beyond the passage being designed to support the ball and also to strike the same, and the basket being capable of folding compactly within the passage.

20

In testimony, that I claim the foregoing 25 as my own, I have hereto affixed my signature in the presence of two witnesses.

LORETTO CORY.
